UNITED STATES PATENT OFFICE.

HENRY L. McCULLOUGH, OF MINNEAPOLIS, MINNESOTA.

FORCE-FEED LUBRICATOR.

1,309,740.

Specification of Letters Patent. Patented July 15, 1919.

Application filed April 16, 1917. Serial No. 162,330.

To all whom it may concern:

Be it known that I, HENRY L. McCULLOUGH, a citizen of the United States, residing at Minneapolis, in the county of Hennepin and State of Minnesota, have invented 5 certain new and useful Improvements in Force-Feed Lubricators; and I do hereby declare the following to be a full, clear, and exact description of the invention, such as 10 will enable others skilled in the art to which it appertains to make and use the same.

My invention relates to force feed lubricators, such as are used for lubricating cylinders, valves, bearings, air compressors, gas 15 engines, and other machinery, and in one sense, is an improvement on or modification of the pump lubricator disclosed and claimed in my Patent No. 872,249, of date, November 26, 1907. The present lubricator, however, 20 differs materially from that of my prior patent in that it involves primary and secondary pumps, the former of which delivers to a sight feed device and the latter of which receives the oil from the said sight feed de- 25 vice.

These primary and secondary pumps involve primary and secondary pump plungers axially seated within a common oscillatory valve, and have threaded engagement there- 30 with, whereby they are given axial movements by relative rotary movements of cer- tain of the parts of the mechanism.

Not only is the arrangement of primary and secondary pumps important because it 35 permits the use of a sight feed device, but it is even more important because it permits of an arrangement in which very ma- terially increased or decreased movements 40 of the secondary pump plunger produced, for example, by varying piston stroke, will not vary the amount of oil supplied by the primary pump.

The preferred form of the improved lubri- 45 cator pump is illustrated in the accom- panying drawings, wherein like characters indicate like parts throughout the several views.

Referring to the drawings:

Figure 1 is a front elevation of the lubri- 50 cator, some parts being broken away;

Fig. 2 is a view chiefly in vertical section

on the line 2—2 of Fig. 1, but with some parts in full;

Figs. 3 and 3^a are end elevations of the valve casing, a valve and primary pump 55 plunger, but illustrating different positions of the parts;

Figs. 4 and 4^a are sections taken on the line 4—4 of Fig. 1, but illustrating different 60 positions of the parts; and

Figs. 5 and 5^a are sections taken on the line 5—5 of Fig. 1, some parts being broken away.

The numeral 6 indicates an oil receiver which, as shown, is of rectangular form and 65 provided with a cover plate 7. The lower portion of one side of the receiver 6 has a large opening that is closed by a casting 8 that projects into the receiver and the flange 70 of which is rigidly secured with a liquid-tight joint to the adjacent wall of the said receiver. The head 8 is formed with an internally tapered valve seating sleeve 9 in which is seated an oscillatory correspondingly tapered valve 10. The valve, respec- 75 tively, in its inner and outer ends, has axially aligned plunger seats 11 and 12 in which, respectively, work with threaded engagement, a so-called primary pump plunger 13, and a so-called secondary pump plunger 14. 80 The projecting end of the primary pump plunger 13 has a radial stop cam 15 against which a washer 16 is seated by a spring 17, the inner end of which is seated against a shoulder on the sleeve 9, so that it not only 85 takes up play between the threads of the pump plunger 13 and the valve, but also keeps the valve tightly drawn into its tapered seat.

One end of the stop pin 15 projects for en- 90 gagement between circumferentially spaced stop lugs 18 and 18^a on the end of the sleeve 9.

The pump plunger 14 projects from the outer end of the valve but is connected thereto under very considerable friction, as shown, by a pliable packing 19, a coiled spring 20 and a spring adjusting cap or packing nut 21, which latter has threaded engagement with the outer end of the said 100 secondary pump plunger. The valve 10 has a projecting annular flange formed with two

stop surfaces 10^a and 10^b that are adapted to engage, respectively, with the end and under side of a threaded stop bolt or screw 23 that works in a lug 24 on the outer side 5 of the casting 8.

In the intermediate portion of its bottom, the sleeve 9 has an oil intake port 25, and at a diametrically opposite upper point, it is provided with a discharge port 26 that is 10 connected to the lower end of a sight feed tube 27, that delivers into the upper portion of a small stand pipe 28. The upper portion 28^a of this stand pipe 28 is preferably of glass, so that the amount of oil 15 taken from the sight tube 27 may be constantly observed. The contracted lower end of the stand pipe 28 is screwed into the casting 8 and delivers to, and in fact constitutes, an upper extension of a secondary oil receiver or chamber 29.

Leading downward from the bottom of the secondary oil receiver or chamber 29 is an oil delivery port 30 that opens into the inner end of the piston seat 12. Leading 25 from the valve seat of the casting 8 is a port or oil discharge conduit 31 that connects to an oil discharge or delivery pipe 32 from which the lubricant will be fed to the place where it is to be used, either directly or 30 through branch pipes.

Before describing the apparatus, attention is called to the fact that the frictional engagement between secondary plunger 14 and valve 10 is materially greater than the frictional engagement between primary plunger 35 13 and said valve and is also materially greater than the frictional engagement between said valve 10 and the sleeve 9.

As a starting point, let it be assumed that 40 the parts are in the relative positions shown in Figs. 1, 2, 3^a, 4^a, and 5^a. Now let it be assumed that the arm 22 is moved from right toward the left, in respect to Fig. 1, far enough to produce the following operations:

At first the valve and both pump plungers move together, or as if one, until the pin 15 strikes the stop 18, whereupon the primary pump plunger 13 will be stopped, 45 but the valve 10, with the secondary pump plunger 14 will still move until the stop 10^a strikes the end of the stop bolt 23, whereupon the said valve will be stopped. Up to this time, the secondary plunger 14 50 has not been moved within the valve, but note, the valve being stopped, and its movement being constantly toward the right, it will be screwed outwardly. Immediately after the above noted movement of the primary pump plunger 13 is stopped, continued movement of the valve 10 will cause 55 said plunger to move outward in its seat 11 at a time when the port 33 is in communication with port 25 and while port 34 is 60 out of communication with port 26. This,

of course, draws the lubricating oil into the primary plunger seat 11. The amount of oil that will be drawn into said seat 11 will depend on the amount of movement given to the valve 10 in the direction stated, after 70 the rotation of the said plunger 13 has been stopped.

The valve 10 is provided with a port 35 which, when the valve is in the position shown in Fig. 5^a, registers with port 31, 75 70 and when said valve is in position shown in Fig. 5, registers with port 30. Up to the time that valve 10 is stopped in its rotation by engagement of stop 10^a with stop bolt 23, the secondary pump plunger 80 14 is not moved within its seat in valve 10. After the above noted movement of said valve has been stopped, further oscillatory movement of arm 22 and plunger 14 will cause the latter to move outwardly in said 85 valve, thereby drawing from secondary oil chamber 29 through ports 30 and 35, then registered, as shown in Fig. 5, into secondary pump chamber 12, and which oil was delivered into said chamber 29 by a 90 previous action of the pump presently to be noted. It, of course, goes without saying, that regardless of the amount of movement given to the arm 22 and plunger 14, after the valve has been stopped in its rotation, 95 the said plunger cannot possibly draw into the secondary pump chamber 12 any more oil than was delivered into the chamber 29 by a previous action of the primary pump plunger.

When arm 22 is moved from its extreme position at the left back toward its extreme position toward the right, the valve 10 and two plungers 13 and 14 will move together until the stop pin 15 strikes stop 18^a, at 105 which time, ports 25 and 33 will be out of registration, and ports 34 and 26 will be in registration. This registration of the valves 26 and 34 will be maintained while valve 10 is being rotated farther toward the 110 right, thereby causing plunger 15 to move inward into seat 11 and to positively discharge oil therefrom, out through sight feed tube 27. At this time, the stop 10^b strikes stop bolt 23, thereby intercepting further 115 movement of valve 10 in the direction last noted, and then stopping valve 10 with port 35 of secondary plunger seat 12 in registration with discharge port 31 (see Fig. 5^a). The valve being now stopped, the arm 22 120 and secondary plunger 14 continue to rotate toward the right, said plunger will be moved inward to its seat, thereby positively ejecting the oil or lubricant from secondary chamber 12 and out through pipe 32.

What I claim is:

1. A pump lubricator comprising a container for the lubricant, an oscillating valve for receiving a quantity of the lubricant from said container and carrying it to a 130

discharge, primary and secondary plungers working in said valve, said secondary plunger operating to force the lubricant to said discharge, and said primary plunger serving to force the lubricant to said secondary plunger.

2. A pump lubricator comprising a container for the lubricant, an oscillating valve for receiving a quantity of the lubricant from said container and carrying it to a discharge, primary and secondary plungers working with threaded engagement in said valve, said secondary plunger operating to force the lubricant to said discharge, and said primary plunger serving to force the lubricant to said secondary plunger.

3. A pump lubricator comprising a container for the lubricant, an oscillating valve for receiving a quantity of the lubricant from said container and carrying it to a discharge, primary and secondary plungers working with threaded engagement in said valve, said secondary plunger operating to force the lubricant to said discharge, and a sight feed device receiving from said primary plunger and delivering to said secondary plunger.

4. A pump lubricator comprising a container for the lubricant, an oscillating valve for receiving a quantity of the lubricant from said container and carrying it to a discharge, primary and secondary plungers working with threaded engagement in said valve, said secondary plunger operating to force the lubricant to said discharge, a sight feed device receiving from said primary plunger and delivering to said secondary plunger, means for oscillating said secondary plunger, means limiting the oscillatory

movement of said valve to a movement less than that of said secondary plunger, and means for limiting the oscillatory movement of said primary plunger to a movement less than that of said valve.

5. A pump lubricator comprising a container for the lubricant, an oscillating valve for receiving a quantity of the lubricant from said container and carrying it to a discharge, primary and secondary plungers working with threaded engagement in said valve, said secondary plunger operating to force the lubricant to said discharge, a sight feed device receiving from said primary plunger and delivering to said secondary plunger, means for oscillating said secondary plunger, means limiting the oscillatory movement of said valve to a movement less than that of said secondary plunger, and means for limiting the oscillatory movement of said primary plunger to a movement less than that of said valve, the frictional engagement between said valve and secondary plunger being greater than that under which said valve is seated and greater than that friction which is between said valve and primary plunger.

6. A pump lubricator comprising a container for the lubricant, a cut-off valve and coöperating primary and secondary plungers, and means for moving said plungers with differently timed actions.

In testimony whereof I affix my signature in presence of two witnesses.
